UNITED STATES PATENT OFFICE.

FREDERICK H. COLBURN, OF CONCORD, NEW HAMPSHIRE, ASSIGNOR, BY MESNE ASSIGNMENTS, TO THE GOVERNMENT OF THE UNITED STATES AND THE PEOPLE THEREOF.

RELIEF-ALIDADE.

1,240,676.

Specification of Letters Patent. Patented Sept. 18, 1917.

Application filed July 25, 1916. Serial No. 111,203.

(DEDICATED TO THE PUBLIC.)

To all whom it may concern:

Be it known that I, FREDERICK H. COLBURN, a citizen of the United States of America, residing at Concord, in the county 5 of Merrimack, State of New Hampshire, whose post-office address is Concord, New Hampshire, have invented a new and useful Improvement in Relief-Alidades.

This application is made under the act 10 of March 3, 1883, chapter 143 (22 Stat. 625), and the invention, herein described and claimed, may be used by the Government of the United States, or any of its officers or employees, in the prosecution of work for 15 the Government, or any person in the United States, without payment to me of any royalty thereon.

My invention relates to relief alidades.

The object of my invention is to provide 20 an apparatus, simple in construction and easy of operation, and one which is specially designed to reproduce a panorama from a given point, upon a field sheet, just as it appears to the observer at that point. It 25 is particularly useful in making the panoramic portion of a mountain look-out map.

The object, characteristic features, and scope of my invention will be more readily understood from the following description, 30 taken in connection with the accompanying drawings, wherein:

Figure 1 is a side elevation.

Fig. 2 is a top plan view of the base.

Fig. 3 is a detail view of the front sight.

Fig. 4 is a vertical longitudinal section 35 of the front sight.

Fig. 5 is a detail view of the rear sight.

Fig. 6 is a vertical longitudinal section 40 of the rear sight.

Fig. 7 is a perspective view showing the maps.

Fig. 8 is a plan view showing the maps.

Referring to the drawings, A represents 45 the base of the alidade, having a projecting pivot B, firmly secured thereto, which fits into a bushing a, in the center of the drawing board, C, in such position as to permit the base, A, to be revolved on said pivot, B. Said base, A, is partly recessed or cut away 50 to the center line, as shown at b in Fig. 2. This recessed portion is divided into suitable graduations, as shown at c, Fig. 2.

The base, A, supports a spirit level, D,

and has threaded apertures, d, for receiving the set screws hereinafter referred to. Two 55 small bosses, e, projecting from the underside of said base, A, together with the collar, e', hold the base, A, parallel to and away from, the drawing board, C.

A front sight, E, is pivotally hinged to 60 one end of the base, A, by means of a spring hinge, f. Secured to the base, A, is a post, F, having an opening, g, for receiving the quadrant, G, which quadrant is securely fastened to the front sight, E. The holes, 65 g', receive the stop, h, thereby regulating the angle of the front sight, E, with reference to the horizontal plane. The front sight, E, has a tube, H, in which is adjusted a movable member, I, having its upper portion threaded, and having a recording needle, J, fixed securely to its lower end. To the apex of member, I, is secured a sight, K. The member, I, is adapted to be raised or lowered, carrying with it the recording 70 needle, J, and the sight, K, by means of adjusting the thumb nut, L, which encircles the tube H and threaded on the inside for engaging the threaded portion of the member I. Said thumb nut, L, is held in operative position by means of ring, i', which is secured to the tube, H. The part, i', is attached to the thumb nut, L, by solder, or other suitable means, the object being to provide means for the thumb nut, L, to rotate freely about the tube, H, without moving longitudinally thereon.

The rear sight, M, is rigidly attached to 85 the base, A, by set screws, j, which engage the threaded holes, d. The rear sight, M, 90 comprises an upright hollow tube, N, the inside diameter of which is made of the proper size to receive a movable member, O. The member, O, consists of a peep sight, P, and the thumb screw, k, which moves up 95 and down in slot, l, allowing the member, O, to be clamped in any of the positions regulated by the graduations of the tube, N. The raising and lowering of the member, O, regulates the height of the peep 100 sight, P.

In practising my invention, I place the drawing board, C, on an ordinary tripod, and place on the drawing board, C, a circular piece of drawing paper, with a radius 105 slightly longer than the distance from the

center pin, B, to the forward sight, E. In the interior of the paper I place a circular base map of the region around the mountain, the panorama of which is desired, and leave a margin of uncovered paper about three inches in width. Then I orient the table according to the interior base map and set up the alidade for use by inserting the pin, B, in the hole in the center of the drawing board, C.

The alidade is first adjusted so as to include within the sighting limits of the alidade all of the panorama visible. This is accomplished in the following manner:

15 With the front sight, E, extended to its limit, I sight through the rear peep sight, P, and raise or lower the sight, P, until the highest point on the skyline is gotten into line of sight, when the member, O, should be secured by tightening the thumb screw, k ; then I return the member I into the tube, H, as far as it will go and sight again through the rear peep sight, P, to ascertain how much of the near country is included 20 in the range of sight. If it is desired to include more of the near country than this adjustment will permit, then the peep sight, P, should be raised, which action will serve, however, to sacrifice the showing of some 25 of the high peaks on the panoramic map. This difficulty can in most cases be obviated by advancing the member, M, so that the set screws, j , engage a pair of the threaded apertures, d , nearer the center of the base, 30 A. To avoid distortion of the panorama, the peep sight, P, must be left in one position until each particular map is finished. As a means of testing the level and orientation of the board as well as the position of 35 the drawing board, C, and the position of the rear sight, M, during the work, direct the alidade successively at several different peaks around the horizon; in each instance bring the front sight, K, into the line of 40 sight of the rear peep sight, P, depress the front sight, E, causing the needle, J, to make a small hole in the recording sheet and label this hole with the name of the peak sighted at. The front sight, E, is usually 45 placed at an angle of 45° to the horizontal. If a larger angle is used, the panorama appears flat; if a smaller angle is used, the panorama is exaggerated vertically. Then starting at some convenient point, it is 50 merely necessary for the operator to sight at successive points along the various topographic elements visible from his station, 55

rotating the alidade and elevating or depressing the front sight, K, to bring it into line with the rear peep sight, P, and depressing the front sight, E, at each sighting to cause the needle, J, to register. In this manner the salient elements of relief of the particular topographic features sighted at will be recorded on the map sheet as a series 60 of pin holes, which, as the work progresses, are joined by a line to complete the relief sketching of those elements. These operations are continued throughout and around the whole field of vision of the operator in 65 such degree of detail as circumstances warrant. The operation is illustrated in Fig. 7 by $m n o v$.

From the foregoing, it is thought that the construction, operation and many advantages of the herein described invention will be apparent to those skilled in the art, without further description, and it will be understood that various changes in the size, shape, proportion, and minor details of construction may be resorted to without departing from the spirit or sacrificing any of the advantages of the invention.

Having thus described my invention, I claim:

1. An alidade comprising a base adapted to be revolvably mounted on a drawing board, a tube hingedly connected to one end of said base, adjustable means to hold said tube yieldingly in predetermined inclined relation to said base, said tube being provided with a slot, a sight member slidably mounted in said tube and having a marking device extending through said slot, a second tube adapted to be fixedly secured in different 90 positions on said base, means for detachably securing said second tube in said base, a sight adjustable in said second tube, and means to secure said sight in adjusted position in said second tube.

2. An alidade comprising a base, a front sight pivotally connected to said base, means connecting said base and sight normally to maintain the sight yieldably inclined to the base, and a vertically adjustable rear sight 105 adapted to be fixedly and vertically secured in different positions on said base.

In testimony whereof, I affix my signature in the presence of two subscribing witnesses.

FREDERICK H. COLBURN.
